UNITED STATES PATENT OFFICE

135,643

DESIGN FOR A COMBINATION PAPER- WEIGHT AND STAMP DISPENSER

Francisco V. Raymundo, Attleboro, Mass.

Application December 10, 1941, Serial No. 104,556

Term of patent 3½ years

To all whom it may concern:

Be it known that Francisco V. Raymundo, a citizen of the Philippine Islands, owing allegiance to the United States, residing at Attleboro, in the county of Bristol and State of Massachusetts, has invented a new, original, and ornamental Design for a Combination Paperweight and Stamp Dispenser, of which the following is a specification, reference being had to the accompanying drawing forming a part thereof.

Fig. 1 is a front perspective view of a combination paperweight and stamp dispenser showing my new design, and

Fig. 2 is a side perspective view thereof.

I claim:

The ornamental design for a combination paperweight and stamp dispenser, substantially as shown.

FRANCISCO V. RAYMUNDO.
